UNITED STATES PATENT OFFICE.

WILLIAM J. RAUM, OF SYRACUSE, NEW YORK.

APPARATUS FOR LUBRICATING CARS.

SPECIFICATION forming part of Letters Patent No. 763,693, dated June 28, 1904.

Application filed October 23, 1903. Serial No. 178,294. (No model.)

To all whom it may concern:

Be it known that I, WILLIAM J. RAUM, a citizen of the United States, and a resident of Syracuse, in the county of Onondaga, in the State of New York, have invented new and useful Improvements in Apparatus for Lubricating Cars, of which the following, taken in connection with the accompanying drawings, is a full, clear, and exact description.

10 The object of this invention is to equip railway-cars with simple and efficient means for applying lubricant in equal quantities and simultaneously to all the journals of the car-truck and to avoid the delay and extra labor 15 of opening the journal-boxes and also guard against waste of lubricant; and to that end the invention consists in the novel construction and combination of the component parts of the lubricating apparatus hereinafter described and as illustrated in the annexed drawings, in which—

Figure 1 is a diagrammatic end view of a railroad-car equipped with my invention. Fig. 2 is a side view of that portion of the car to 25 which my invention is applied. Fig. 3 is an enlarged transverse section of the lubricant-distributing case. Fig. 4 is a detail view of the application of the lubricant-ducts to the journal-boxes of the car.

30 A represents the car-body, which may be of any ordinary form now in use.

B denotes one of the car-tracks, which may also be of any well-known construction.

a a denote the journal-boxes of the car. It 35 is the supply of the lubricant to these boxes for which my invention is designed. To effect this supply in an expeditious and convenient manner and without requiring the journal-boxes to be opened, I employ a lubricant case or reservoir R, which I secure in a safe and convenient position inside of the car, as 40 represented in Fig. 1 of the drawings. The top of this reservoir is provided with an opening through which to charge the reservoir 45 with oil. Said opening is provided with a suitable removable cover a'. A glass gage b is attached to the reservoir for the purpose of showing the supply of oil therein.

c represents the main lubricant-pipe, which leads from the reservoir to a lubricant-distributing case d, suitably secured to the car beneath the body A. A stop-cock or suitable valve e is connected to the main pipe c for controlling the flow of lubricant. The interior of the distributing-case d is provided with 50 walls f f, which meet central under the inlet of the main pipe c and are inclined to the bottom of opposite sides of the case, as shown in Fig. 3 of the drawings. The aforesaid arrangement of the walls f f causes the inflowing lubricating-oil to be equally divided and conducted in separate streams to opposite sides of the case d. To the bottom parts of these walls are attached the ducts h h, which lead to the journal-boxes a a at opposite sides 55 of the truck and terminate in branch ducts entering the journal-box in front and rear of the journals j and supply the oil thereto.

By the use of the described lubricating apparatus a person can supply the journal-boxes 70 with lubricant by merely turning the valve e to allow the lubricant to flow from the reservoir R through the main duct c to the distributing-case d, which delivers the oil in equal quantities to the ducts h h, which convey the 75 oil to the journal-boxes a a. By observing the gage b the person in charge can readily note the amount of lubricant supplied to the journal-boxes, and by closing the valve e at the proper time overflow and waste of lubricant from the journal-boxes is obviated.

What I claim as my invention is—

The combination with a railway-car, of a lubricant-reservoir attached to said car, a main pipe leading from said reservoir, a distributing-case connected to said pipe, ducts leading from said case to the journal-boxes, there being walls in said distributing-case dividing the inflowing lubricant into separate streams of equal volumes and conducting the same to the 90 aforesaid ducts as set forth.

WILLIAM J. RAUM.
